Attnys.

UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

1,387,123.

Specification of Letters Patent.

Patented Aug. 9, 1921.

Application filed January 16, 1920. Serial No. 351,794.

To all whom it may concern:

Be it known that I, FRED S. CARR, a citizen of the United States, and resident of Newton, in the county of Middlesex and 5 Commonwealth of Massachusetts, have invented an Improvement in Separable Fasteners, of which the following description, in connection with the accompanying drawings, is a specification, like characters on 10 the drawings representing like parts.

This invention pertains to improvements in separable fasteners, and more particularly, though not exclusively, to improvements in the securing of separable fasteners 15 to carrying fabrics while providing certain advantages hereinafter more fully described.

In the drawings, which show a preferred embodiment of my invention:

Figure 1 is an elevation of two pieces of 20 fabric held together by a preferred form of fastener;

Fig. 2 is a section on the line 2—2 of Fig. 1;

Fig. 3 is a section on the line 2—2 of 25 Fig. 1, where the stud is entered in the socket from the opposite side from that shown in Fig. 2;

Fig. 4 is a plan view of the preferred form 30 of stud shown in Fig. 2;

Fig. 5 shows the parts of the stud and 35 stud-securing means in the position which they assume prior to assembly;

Fig. 6 is a plan view of the preferred form 40 of socket herein described; and

Fig. 7 is a diagrammatic view of the 45 socket and socket-securing parts in their relation prior to assembly thereof and securing of the socket to the fabric.

Referring to the drawings and to the preferred form of my invention selected for 50 illustrative purposes, I have shown a stud 8 preferably secured to the stud-carrying fabric 9 by a flanged stud-securing plate 11 into which the expansible base 10 of the stud 45 is adapted to be expanded, to crowd the stud-carrying fabric 9 within the stud-securing part 11. The method of assembling the stud with its fabric is illustrated diagrammatically in Fig. 5, it being understood 55 that the stud base 10 is adapted to be flattened when pressure is applied thereto to assume the position shown in Fig. 2.

Coöoperating with the preferred form of 55 stud hereinbefore described, I preferably provide a socket which may include a

spring-containing casing 12 containing a spring 13 adapted to intersect portions of a stud-receiving aperture 14 which may be and preferably is notched as shown to provide a lateral lock, as provided in my co-pending 60 application Serial No. 307,111, filed June 27, 1919.

The preferred form of casing may be secured to the goods by expansible socket-securing means 15 adapted to crowd the fabric within the rim of the casing 12 at points not occupied by the spring 13. The socket-securing plate 15 is also preferably provided with a stud-receiving aperture, also notched, so that, where the fabric is apertured opposite the stud, the latter may be entered in the casing either from the side shown in Fig. 2 or from the side shown in Fig. 3.

It will be understood that I use the word "fabric" in its broader sense to include not 75 only woven materials, but any flexible carrying medium.

While I have shown and described a preferred form of one embodiment of my invention, it will be understood that changes 80 involving omission, substitution, alteration and reversal of parts, and even changes in the mode of operation, may be made without departing from the scope of my invention, which is best defined in the following 85 claims.

Claims:

1. A separable fastener comprising, in combination, a stud having a head and a neck; a socket having a spring-containing 90 casing containing a spring and having plates on each side of the spring, each of said plates being apertured to receive the head of the stud, the sides of each aperture being notched and said stud enterable into said 95 socket from either side.

2. A separable fastener comprising, in combination, a stud having a head and a neck; a socket having a spring-containing 100 casing containing a spring and having plates on each side of the spring, each of said plates being apertured to receive the head of the stud, the sides of each aperture being notched and said stud enterable into said 105 socket from either side, one of said plates flanged to provide a marginal recess and the other adapted to grip the socket-carrying fabric in said recess.

3. A separable fastener comprising, in combination a stud having a head and a neck; 110

5 a socket having a spring-containing casing containing a spring and having plates on each side of the spring, each of said plates being apertured to receive the head of the stud, the sides of each aperture being notched and said stud enterable into said socket from either side, one of said plates flanged to provide a marginal recess and the other adapted to grip the the socket-carrying fabric in said recess at points not occupied by the spring.

10 4. A separable fastener comprising, in combination, a stud having a head and a neck; a socket having a spring-containing casing containing a spring and having plates on each side of the spring, each of said plates being apertured to receive the head of the stud, the sides of each aperture being notched and said stud enterable into said socket from either side, said spring engaging the stud substantially at the same point whether entered from one side of said socket or from the other side thereof.

15 5. A separable fastener comprising, in

20 combination, a stud having a head and a neck, and a socket adapted to be secured to a carrying fabric and when so secured permitting engagement of said stud with the socket from either side thereof, said stud having its base received behind the general plane of its carrying fabric, and said socket offset substantially entirely to one side of the general plane of its carrying fabric.

25 6. A fastener including a stud having a head and a neck, in combination with a 30 socket including a dished plate having a rim, a spring in said dished plate, a securing plate for gripping the fabric to which the socket is secured beneath the rim of the dished plate, said securing plate having an 35 opening therethrough in line with an opening through the fabric, whereby said stud may engage said spring on being entered in the socket through the securing plate and through the fabric.

40 45 In testimony whereof, I have signed my name to this specification.

FRED S. CARR.
